UNITED STATES PATENT OFFICE.

JOSEPH LAMONTAGNE, OF NORTHAMPTON, MASSACHUSETTS, ASSIGNOR OF
TWO-THIRDS TO ARTHUR J. LAMONTAGNE AND AVON C. MATTHEWS,
OF SAME PLACE.

SWITCH-OPERATING MECHANISM FOR CARS.

SPECIFICATION forming part of Letters Patent No. 591,233, dated October 5, 1897.

Application filed April 26, 1897. Serial No. 634,039. (No model.)

To all whom it may concern:

Be it known that I, JOSEPH LAMONTAGNE, a subject of the Queen of Great Britain, residing at Northampton, in the county of Hampshire and State of Massachusetts, have invented certain new and useful Improvements in Switch-Operating Mechanism for Cars, of which the following is a specification.

My invention relates to a switch-operating mechanism for cars or mechanism for operating or moving the switch where the rails of one track lead into or connect with the rails of another track; and the object of my invention is to provide a switch-operating mechanism adapted to be combined with the car, and more particularly with a street-car, which may be operated by the motorman or driver of the car to move or throw the switch as the car approaches and cause the car to travel on one track or the other, as desired.

My invention consists in certain novel features of construction of my switch-operating mechanism applied to a car, as will be hereinafter fully described.

Referring to the drawings, Figure 1 shows one end of a car with my switch-operating mechanism combined therewith. The mechanism is shown in its inoperative position. Fig. 2 shows the switch-operating mechanism shown in Fig. 1 in its operative position. Fig. 3 is a horizontal section on line 3 3, Fig. 1, looking in the direction of arrow *a*, same figure. Fig. 4 is a plan view of the end of the platform detached, looking in the direction of arrow *a*, Fig. 1. Fig. 5 shows one rail of a track and a pivoted switch of ordinary construction and a second rail leading off from the switch portion of the track. The switch is shown in position to cause the car to travel on the main rail. Fig. 6 corresponds to Fig. 5, but the switch is shown in the opposite position to cause the car to travel on the side rail. Fig. 7 corresponds to Fig. 5, but shows my switch-operating device in the opposite position. Fig. 8 is a detached portion of the switch-operating mechanism, looking in the direction of arrow *b*, Fig. 1. Fig. 9 is a partial sectional view of the switch-operating mechanism shown in Figs. 1 and 2. Fig. 10 is a section on line 10 10, Fig. 9, looking in

the direction of arrow *c*, same figure. Fig. 11 is a bottom view of the device for engaging the switch. Fig. 12 is a modified construction of the horizontal bars shown in Fig. 9; and Fig. 13 is a section on line 13 13, Fig. 12, looking in the direction of arrow *d*, same figure. Figs. 8 to 13, inclusive, are shown on an enlarged scale.

In the accompanying drawings, 1 is one end of a car, in this instance shown as a street-railway car, having the platform 2 at one end and the truck 3 of ordinary construction. My switch-operating mechanism is applied to the under part of the car, at the end thereof, and consists of the switch-engaging device 4, which is preferably made of the shape of a head (shown in the drawings) having one side 4' rounded and the other side 4" formed with a depending lip or flange 4'', which is adapted to extend below the top of the rail when the mechanism is in operation.

The elongated portion of the device 4 is made of angular shape, as shown in Fig. 11, or with inclined surfaces to form a sharp or knife edge to pass between the inner face of the rail and the front end of the switch, as shown by dotted lines in Figs. 5 and 6. The switch-engaging device 4 has a stem 5 extending up therefrom, which is secured in a tube 6 by pins 7 or otherwise. The tube 6 has a vertical reciprocating motion in a second tube or cylinder 8, which is pivotally supported at its upper end by screws 9 in the hub or collar 10 on the stand 11, secured to the end of the truck 3. The lower end of the tube or cylinder 8 extends loosely through a collar 12, secured below the collar 10, and is held in proper position therein, but permitted to have a slight side motion by two oppositely-arranged springs 13, secured at their upper ends to the tube 8 and extending through the collar 12 and bearing at their lower ends on said tube. (See Fig. 8.)

In the upper end of the reciprocating tube 6 is secured the lower end of a rod 14, which is provided with a screw-thread on which is screwed the hub of a sprocket-wheel 15, which is secured by a set-screw 16. (See Fig. 9.) The upper end of the rod 14 extends through a slot in the bar 17, (see Fig. 3,) and a nut 18

is screwed onto the end of the rod 14 and holds the end of the bar 17 between the sprocket-wheel 15 and a washer 19 below the nut 18 to cause the sprocket-wheel 15, rod 14, 5 tube 6, and switch-engaging device 4 to move up or down or have a reciprocating motion, according as the end of the bar 17 is raised or lowered.

The bar 17 is pivoted at about its middle 10 part in the lower end of a bracket 19, secured upon the under side of the car. The other end of the bar 17 is pivotally connected by a pin or screw 20 to the inner end of a second bar 21, which is also pivotally supported at 15 about its middle part in the lower end of a bracket 22, secured to the under side of the car. (See Figs. 1 and 2.) The outer end of the bar 21 is also provided with a slot, through which extends the lower end of the rod 22, 20 and upon the lower end of said rod 22 is secured the sprocket-wheel 23 by a set-screw 24. The upper end of the rod 22 is secured by pins 25 or otherwise within the lower end 25 of the tube 26, which has a vertical reciprocating motion within the cylinder or tube 27, extending through an opening in the platform and secured therein. (See Fig. 9.)

Upon the top of the tube 26 is secured a gear 28. A spiral spring 29 encircles the tube 30 26 and extends between the gear 28 and the flanged head of the cylinder 27. The spring 29 acts to keep the tube 26 in its raised position, with the rods 21 and 17 straight and in the position shown in Fig. 1, the switch-engaging device 4 being out of engagement with the rail.

The motorman or driver by pressing his foot on the gear 28 pushes down the tube 26 and the outer end of the bar 21 and throws 40 up the inner end of said bar and also the inner end of the bar 17, as shown in Fig. 2, causing the tube 6 to be pushed down, carrying down the switch-engaging device 4, which will bear or ride on the rail, and the front 45 edge of the flange 4" will engage and move the switch 35, as shown in Figs. 5, 6, and 7.

The parts above described are duplicated, as shown in Fig. 3, so that there will be a switch-engaging device on each side of the 50 car and also at each end of the car.

In order to give a half-turn to the switch-engaging device 4 to cause it to change from the position shown in Fig. 6, where the switch is moved in one direction to cause the car to travel on the side track to the position shown 55 in Fig. 7, where the switch is moved in the opposite direction, as shown in Fig. 7, to cause the car to travel on the main track, a barrel-gear 30 is arranged between the two 60 gears 28 28 to mesh with each of said gears, as shown in Fig. 4, and a vertical handle-bar 31 is connected with said gear 30 to operate the same. The two sprocket-wheels 23 and 15 are connected by a chain 32. (See Figs. 65 1, 2, and 3.) It will be seen that by giving a half-revolution to the barrel-gear 30 through the handle-bar 31 each of the gears 28 will

be given a half-revolution, and through the chain 32 the tube 6, carrying the switch-engaging device 4, will be given a half-revolution, and the switch-engaging device 4 will also be given a half-revolution to change it from the position shown by full lines in Fig. 6 to the position shown by full lines in Fig. 7. By pivoting the bars 17 and 24 substantially 75 midway of their lengths their opposite ends will move vertically in unison or the same distance, and the sprocket-wheels 15 and 23 will keep in the same horizontal plane relatively to each other and the chain 32 will be 80 prevented from binding or running off of either of the wheels.

In order to vary the length of the bars 17 and 21 for different lengths of cars, I may 85 make each of said bars in two parts adapted to slide on each other and connected and secured together, after being adjusted, by the strap or collar 33 and set-screws 34, as shown in Fig. 12.

The operation of my switch-operating mechanism will be readily understood by those skilled in the art.

In the ordinary travel of the car the switch-engaging device 4 will be out of contact with the rail and supported above the rail, as 95 shown in Fig. 1. As the car approaches the switch, supposing the switch-engaging device 4 to be in the position shown by full lines in Fig. 5 and it is desired to throw the switch to cause the car to travel on the track leading off from the main track, the car-operator just before the car reaches the switch presses down with his foot the right-hand gear 28 and causes, through the intervening connection, the engaging device 4 to be pushed down 105 and engage the rail, with the flanged portion extending below the top of the rail on the outer edge thereof, as shown in Fig. 2. The continued travel of the car causes the front knife-edge of the device 4 to pass in between 110 the front or free end of the switch 35 and the edge of the rail, (see dotted lines, Fig. 5,) and the inclined portion of the device 4 will move the switch into the position shown in Fig. 6 and cause the car to travel on the side-track. The operator then removes his foot and the spring 29 raises the gear 28 and also 115 the engaging device 4, through the intervening connections, out of contact with the rail. Supposing the engaging device 4 to be in the position shown in Fig. 5 and the switch 35 in the position shown in Fig. 6 and it is desired to move the switch to cause the car to travel on the main track, the operator gives a half-turn to the handle 31, and this, through intervening connections, as above described, 120 gives a half-turn to the device 4 and moves it into the position shown by dotted lines in Fig. 6, so that the knife-edge of said device will pass in between the free end of the switch 35 and the inner edge of the supplemental rail and move the switch into the position 125 shown in Fig. 7, so that the car will continue to travel on the main track.

It will be understood that the details of construction of my switch-operating mechanism may be varied, if desired, and the same may be applied to cars propelled by any kind of power.

Having thus described my invention, what I claim as new, and desire to secure by Letters Patent, is—

1. The combination, with a car, of a tripping device, a vertically - movable rotary switch-throwing device, and a chain for connecting the same, and means for moving the two devices vertically in unison with each other, substantially as set forth.
- 15 2. The combination, with a car, of a vertically-movable shaft, means upon the upper end thereof for rotating the same and moving it longitudinally, a vertically-movable rotary switch-throwing mechanism, and a chain for connecting said mechanism with the shaft, substantially as set forth.
- 25 3. The combination, with a car, of a vertically-movable spring-actuated shaft, each end of which is provided with a wheel, means for engaging with the upper wheel and rotating the shaft, a vertically-movable rotary switch-throwing device, the upper end of which is provided with a wheel, in the same horizontal plane with the wheel upon the lower
- 30 end of the shaft, a chain upon said wheels, and means for moving the wheels vertically in unison, substantially as set forth.
4. The combination, with a car, of a ver-

tically-movable shaft, a wheel upon each end thereof, a spring between the upper wheel 35 and the platform of the car, a handle provided with a barrel-wheel in engagement with a wheel upon the upper end of the shaft, a vertically-movable rotary switching device provided with a wheel, and means for connecting said wheel with the lower wheel upon the shaft, substantially as set forth.

5. The combination, with a car, of two vertically-movable shafts, the upper end of each of which is provided with a gear-wheel, a handle, the lower end of which is provided with a barrel-gear in engagement with said wheels, two vertically-movable switch-throwing devices, and means for connecting each of said devices with its respective shaft, substantially as set forth.

6. The combination, with a car, of a vertically-movable shaft, a sprocket-wheel upon the lower end thereof, a vertically-movable shaft, the lower end of which is provided with 55 a switching device and the upper end is provided with a sprocket-wheel, interlocking bars secured at their central portions to the car, the opposite ends of said bars being slotted and engaging with the shafts, and a 60 sprocket-chain upon the sprocket-wheels, substantially as set forth.

JOSEPH LAMONTAGNE.
